(57) **CLAIM**

The ornamental design for a collar for thyroid stimulation, as shown and described.

DESCRIPTION

FIG. 1 is a front and top perspective view of a first embodiment of a collar for thyroid stimulation showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front view showing the collar for thyroid stimulation in its wearing environment.

The zipper shown in broken lines in the drawings is an unclaimed feature of the article to which the design is applied.

1 Claim, 6 Drawing Sheets
